MULTIPLE CORE VENTING MACHINE

Anthony Wayne Connor, Tampa, Fla.

Application May 2, 1932. Serial No. 608,741

7 Claims. (Cl. 22—39)

The present invention has for its object to provide a simple, inexpensive, accurate, and efficient mechanism for forming vents in cores used in casting.

5 In the ordinary procedure, cores have been provided with vents by thrusting a venting wire by hand into the finished core, and it frequently happens that the wire thus used pierces the side of the core or is not accurately placed to form the 10 vent in the right location within the core, with resultant defects in the casting.

The apparatus herein illustrated and described comprises a movably mounted clamping member within which a plurality of venting wires of 15 proper length are held accurately spaced to enter a plurality of cores at the precise point desired in each core. The cores are held within the core box in which they are formed; the box is positioned by a gage or gages; and the movement of the venting wires is guided and limited so that the venting 20 holes are made uniform in size, depth, and location.

Two preferred embodiments of the invention are illustrated in the accompanying drawing 25 forming a part of the specification, but it will be understood that the invention is not limited to the details shown, since it will be obvious to those skilled in the art that each element is capable of modification to suit different conditions without 30 losing any of the advantages of this invention or departing from its essential principles.

In the drawing, Figure 1 is a front elevation of a machine in which the venting wires are guided in vertical movement by a sliding frame operated 35 by a foot lever, a core box being shown in position against side and end gages with one side removed, and one core being shown in section; Fig. 2 is a side elevation of the device of Fig. 1; Fig. 3 is a plan view of Fig. 1; Fig. 4 is a fragmentary front elevation of a modification in which a hand lever is used to cause the sliding movement of the frame; Fig. 5 is a side elevation of the modification shown in Fig. 4; Fig. 6 is a plan view on a 40 larger scale of the clamp for the venting wires; Fig. 7 is a side elevation of the clamp of Fig. 6; and Fig. 8 is a plan view of a slotted plate which may be used beneath the core box.

Upon a work table 1 is bolted or otherwise secured 50 a guiding framework having a base 2 and slotted vertical standards 3 which may be connected at the top by a cross bar 4 acting as a stop to limit the upward movement of the sliding bar 5. The bar 5 is shown as having at each end a pivot screw 6 for a link 7, each link at its lower end being pivoted to a yoke 8 which is connected

by a rod 9 to a foot lever 10, normally held lifted by a spring 11.

To the lower side of the sliding bar 5 is secured one element 12 of a clamp, as by screws 13, a second clamp element 14 being adjustably secured 60 to the element 12 as by screws 15. The confronting faces of the elements 12 and 14 are provided with spaced grooves 16 each adapted to receive one end of a venting wire 17. With the screws 15 loosened, the ends of the venting wires may be put 65 into or taken out of the grooves for adjustment to give any desired spacing. Wires of different lengths will be provided from which to choose those suited to reach to the desired depth in the cores when the sliding bar is moved downward 70 into contact with the top of the core box.

A core box 18 is shown in Fig. 1 with one half removed to show the seven spaces 19 within which cores 20 are formed before the box is placed against the adjustable gages 21 and 22 at one side 75 and one end respectively. The venting wires are illustrated in Fig. 1 as spaced within the clamp at distances apart equal to the distances from center to center of the spaces 19 in the core box 18.

Each wire is shown as having a conical washer 80 23 adapted to form an enlargement at the entrance to the vent in the core, to act when the cores are inverted as a means for preventing sand from filling the vent. Cores are frequently stood on end and when the vent is small, particles of 85 sand may wedge in the entrance, this necessitating careful cleaning out by hand.

The core 20 at the left end of the box in Fig. 1 is shown in section formed with a venting opening extending to a point a little distance above 90 the lower end of the core. In some instances, it may be desired to have the vent extend completely through the core, and for this purpose, a plate 24 having a central slot 25 which may be filled with cork or rubber 26, is secured to 95 the base beneath the venting wires so that when the wires are longer than the cores, the cork or rubber will allow the ends of the wires to enter without injury while holding back the sand. The core box may act as a limiting means to determine 100 the downward movement of the cross bar 5 and the wires, or other well known means may be used. Since all the wires move in unison, the depth of the venting opening will be the same when wires of equal length are used.

In the modification shown in Figs. 4 and 5, a hand lever 27 upon a rockshaft 28 acts through a segmental gear 29 meshing with a rack 30 secured to the sliding bar 5 to raise or lower the bar 5 with its venting wires. It will be 110 evident that other hand-operated means may be

used and motor drive when desired in ways needing no illustration.

It will be seen that the mechanism illustrated provides a simple and readily operated group of 5 agencies for moving a spaced plurality of venting tools through a definite path to a predetermined limit, and for holding one or more cores in a definite position or positions to receive each a venting tool simultaneously.

10 In the appended claims, it is intended to claim the invention broadly within the full scope and meaning of the terms employed and not to limit the invention to the precise apparatus shown.

I claim:

15 1. A multiple core venting machine comprising a movable bar, a clamp secured to the bar and adapted to receive a plurality of venting tools and to hold them in spaced position, means for guiding the movement of the bar, and means 20 within the path of movement of the bar for holding a plurality of cores in spaced position to receive the venting tools said holding means forming a stop to limit the movement of the bar.

25 2. A multiple core venting machine comprising a movable clamp having a plurality of spaced grooves adapted to receive venting tools to hold them selectively in definite spaced positions, means for guiding the movement of the clamp, 30 and means within the path of movement of the clamp for holding a plurality of cores in spaced positions to receive the venting tools, said holding means limiting the movement of the clamp and the spacing of the tools bearing a definite 35 relation to the spacing of the cores.

3. In a core venting machine, means for moving venting tools in a predetermined path, means for holding cores within the path of movement of the venting tools, and a support to receive the 40

cores having a portion formed of an elastic material capable of penetration by the tools.

4. In a core venting machine, a venting tool having secured at its base means of greater diameter than the tool for entering the end of a core to form an enlargement of one end of the venting passage.

5. In a core venting machine, a clamp for holding a venting wire, a conical washer mounted upon the wire adjacent to the clamp, a core box within the path of movement of the clamp having a space to hold a core and acting as a stop for the clamp, and means for moving the clamp into contact with the core box, whereby to form an enlargement of the vent in the core 90 at the end adjacent to the clamp.

6. A means for venting cores comprising, a core box for holding a plurality of cores, a clamp mounted for movement toward and from the core box, the core box being within the range of movement of the clamp and acting as a stop to limit the movement of the clamp, and a plurality of wires of uniform length less than that of the core secured within the clamp, whereby the depth of penetration of the cores by the wires 105 may be predetermined.

7. A multiple core venting machine comprising a sliding bar, guideways for the bar, means for moving the bar in its guideways, a clamp carried by the bar, venting tools carried by the 110 clamp, a core box within the path of movement of the bar adapted to hold a plurality of cores in position to receive the venting tools and acting as a stop to limit the movement of the bar, and means for gaging the position of the core 115 box in relation to the path of movement of the tools.
